(57) CLAIM

The ornamental design for a surface pattern for a casino table, as shown and described.

DESCRIPTION

FIG. 1 is a top plan view of the ornamental surface pattern for a casino table;

FIG. 2 is an enlarged view of an ornamental surface pattern as shown in FIG. 1; and,

FIG. 3 is an enlarged view of an ornamental surface pattern depicting an exemplary player betting location. The broken lines showing the casino table are for illustrative purposes only, and form no part of the claimed design.

1 Claim, 2 Drawing Sheets

FIG. 1

FIG. 2FIG. 3
